ELECTRICAL CONNECTOR

Eisuke Takano, Tokyo, Japan, assignor to Nippon Electric Company Limited, Tokyo, Japan, a corporation of Japan

Filed Dec. 24, 1962, Ser. No. 246,778
9 Claims. (Cl. 339—256)

This invention relates to electrical connectors.

When interconnecting various electric circuits of two components, it is important that the connectors employed have good mechanical stability and reliability of connection. Accordingly, it is an object of this invention to provide a connector having such characteristics by means of a novel construction which employs a coil spring and a tongue shaped plug terminal which is designed for cooperative engagement with said spring.

All of the objects, features and advantages of this invention and the manner of attaining them will become more apparent and the invention itself will be best understood by reference to the following description of an embodiment of the invention taken in conjunction with the accompanying drawing, in which

FIG. 1 shows a plug member and a receptacle member of an electrical connection constructed in accordance with the invention, FIG. 1a showing a side elevation of the plug member, FIG. 1b showing in vertical section the receptacle member, and FIG. 1c showing a cross section taken on the line 1c—1c of FIG. 1b;

FIG. 2 shows the electrical connector in its connected position, FIG. 2a showing a vertical section, while FIG. 2b shows a cross section taken on line 2b—2b of FIG. 2a;

FIG. 3 is an exploded view of another plug member and another receptacle spring assembly constructed in accordance with the invention, FIG. 3a showing the plug member, FIG. 3b showing the receptacle terminal member together with a portion of the plug member, FIG. 3c showing a coil spring, and FIGS. 3d and 3e showing cross sections taken respectively on lines 3d—3d and 3e—3e of FIG. 3c; and

FIG. 4 shows still another plug and receptacle member constructed in accordance with the invention, and in which FIG. 4a shows the plug member, FIG. 4b shows the receptacle member, and FIG. 4c shows a cross section taken on line 4c—4c of FIG. 4b.

Referring first to FIG. 1a, an electrical connector constructed in accordance with the invention includes a twisted tongue-shaped plug terminal 1 made by twisting a suitable metal strip, and a supporting member 2 therefor made of insulating material which is fixedly attached to a portion of the plug terminal 1. The supporting member 2 may be provided with a plurality of plug terminals 1 if desired, for making a plurality of connections. Referring next to FIG. 1b, a receptacle member shown therein in vertical section comprises an insulator structure 5, and a coil spring 3 made by winding a piano wire or a wire of Phosphor bronze, German silver, or other suitable resilient material into a helix having an elliptical cross section as shown in FIG. 1c. The coil spring 3 is disposed in a cylindrical channel provided in the insulator structure 5 and a terminal member 4 is soldered or otherwise attached to the coil spring at its right end, and extends through the right end of the insulator body. The insulator structure 5 may, if desired, include a plurality of the coil springs 3. The surface of the plug terminal 1 and the coil spring 3 are preferably plated with gold, silver, platinum, rhodium or other suitable contact material.

It will be obvious that connection will be made when the part shown in FIG. 1a is inserted to the right into the assembly shown in FIG. 1b, as shown in FIG. 2a. As shown in FIG. 2b, which is a cross-sectional view of the receptacle assembly, the coil spring 3 deforms in accord-

2

ance with the twisted form of the plug terminal 1. Firm contact is made as a result of the stress that is produced in the individual turns of the coil spring 3 by the twist deformation produced by insertion of the plug 1. Such twist deformation results in contact by each turn of the helix of the spring 3 with the plug terminal 1 and plays a very important role in enhancing the reliability of the overall electrical contact between the opposite ends of the connector. More particularly, the twist of the plug terminal 1 gives each helical turn of the coil spring 3 a given twist displacement, with the result that the latter is brought into contact with the former at two points for each turn; thus for a coil spring 3 having n number of turns, contact with the plug terminal 1 will be made at $2n$ points under ideal conditions. Thus, the plug terminal 1 and the coil spring 3 combination will be produce very stable electrical contact, so that reliability of contact is excellent even under conditions of mechanical shock.

Further, contact between the plug terminal 1 and coil spring 3 at a multiplicity of points makes it possible to attain with relatively low contact pressure per point of contact, higher reliability of electrical contact than is achieved with the usual contact arrangements in prior art electrical connectors, which conventionally have only one or two contact points. This results in less abrasion of the contacting portions of the plug terminal 1 and coil spring 3 and thereby enhances the useful life of the connector of this invention. This connector has another merit in that the helical form of the coil spring 3 allows the same to yieldably deform in accordance with the form of the plug terminal 1. This has the advantage of producing only a relatively small bending force on the plug terminal 1. Furthermore, the contact pressure given by the twist deformation between the plug terminal 1 and coil spring 3 insures reliability of the contact obtained after connection of the connector, even though the plug terminal 1 before insertion thereof into the coil spring 3 may have some distortion in its actual physical dimensions compared with its ideal shape.

40 Referring now to FIG. 3 which shows an electrical connector in accordance with another embodiment of the invention, a plug terminal is shown in FIG. 3a which is a modification of the plug terminal 1 illustrated in FIG. 1a and includes a slot 6 provided along the center of the tongue-shaped body with a view to furnishing the plug terminal 1 with resiliency in the direction of its width. After insertion of the plug terminal 1 into the coil spring 3, elastic deformation of the plug terminal 1 in the direction of the width results in better contact.

50 In FIG. 3b, a modified receptacle terminal member 4' is provided with a concave portion at its inner end where it is coupled with the coil spring 3 so that the concave portion may become engaged with the convex end portion of the plug terminal 1 after it has been pushed into the coil spring 3 in the manner illustrated. According to this modification, the coil spring 3 may be made shorter than that for use in the above illustrations where the inner end portion of the terminal member is flat rather than concave.

60 In FIG. 3c a modified composite coil spring is shown and comprises two individual interleaved helical springs 9 and 10, so that the torsional rigidity and the reliability of contact between the plug terminal 1 and the composite coil spring may be increased. This is achieved because of the function of the individual springs as a pair of twin contacts independent of each other between the plug terminal 1 and the composite coil spring. The spring may also consist of more than two individual springs. In this embodiment, see FIG. 3c, the cross section of the spring taken on line 3d—3d is greater in size than that at line 3e—3e as shown in FIGS. 3d and 3e, respectively, this construction providing ease of

introduction of the plug terminal 1 into the coil spring 3.

Referring now to FIG. 4, which shows further modifications of the plug terminal 1 and coil spring 3, a plug terminal 11 is provided which is not twisted, see FIG. 4a, while a coil spring 12 is illustrated in FIGS. 4b and 4c which is twisted in lieu thereof. FIG. 4c shows a cross section taken on line 4c—4c of FIG. 4b. Excellent contact characteristics are attained when the plug terminal 11 is pushed into the coil spring 12.

While the foregoing description sets forth the principles of the invention in connection with specific apparatus, it is to be understood that the description is made only by way of example and not as a limitation of the scope of the invention as set forth in the objects thereof and in the accompanying claims.

What is claimed is:

1. An electrical connector comprising at least one helically wound metal spring member having a portion with an elliptical cross section, and an elongate metal plug member adapted for insertion into said spring member, one of said members being axially twisted, said plug member having a set of opposite edges for engaging the individual coils of said spring member, said plug member further having a width approximately equal to the major axis of said elliptical cross section to cause torsional displacement of spaced coils relative to one another upon insertion of said plug member into said spring member, whereby contact pressure between said edges and said coils is produced by said torsional displacement upon insertion of said plug member as aforesaid.

2. An electrical connector as set forth in claim 1 wherein the orientation of the coils about the longitudinal axis of said spring member varies along the length thereof when said spring member is in an unbiased condition.

3. An electrical connector as set forth in claim 1 which further includes a second helical spring having its individual coils disposed in interlaced relationship with the coils of said spring member.

4. An electrical connector as set forth in claim 1 wherein the major axes of adjacent coils of said spring member are disposed at progressively different angular positions about the longitudinal axis of said spring member, to produce a twisted shape in said spring member in the absence of said plug member.

5. An electrical connector comprising at least one helically wound metal spring member having an elliptical cross section when viewed axially thereof, and at least one elongate metal plug member adapted for insertion into said spring member, said plug member being axially twisted, said plug member having a set of opposite edges for engaging the individual coils of said spring member, said plug member further having a width approximately equal to the major axis of said elliptical cross section to cause torsional displacement of spaced coils relative to one another upon insertion of said plug member into said spring member, whereby contact pressure between said edges and said coils after insertion of said plug member into said spring member is afforded by said torsional displacement of said spring member.

6. An electrical connector comprising at least one helically wound metal spring member having an elliptical cross section when viewed axially thereof, said spring member being axially twisted when in an unbiased condition, and at least one elongate metal plug member adapted for insertion into said spring member, said plug member having a set of opposite edges for engaging the individual coils of said spring member, said plug member further having a width approximately equal to the major axis of said elliptical cross section to cause torsional displacement of spaced coils relative to one another upon insertion of said plug member into said spring member, whereby contact pressure between said edges and said coils after insertion of said plug member

into said spring member is afforded by said torsional displacement of said spring member.

7. An electrical connector comprising at least one helically wound metal spring member having an elliptical cross section when viewed axially thereof, and at least one elongate metal plug member adapted for insertion into said spring member, one of said members being axially twisted, said plug member having a set of opposite edges for engaging the individual coils of said spring member, and a longitudinal slot between said edges, said plug member further having a width approximately equal to the major axis of said elliptical cross section to cause torsional displacement of spaced coils relative to one another upon insertion of said plug member into said spring member, whereby contact pressure between said edges and said coils after insertion of said plug member into said spring member is afforded by said torsional displacement of said spring member.

8. An electrical connector comprising at least one helically wound metal spring member having an elliptical cross section when viewed axially thereof, at least one elongate metal plug member adapted for insertion into said spring member, one of said members being axially twisted, and a terminal member coupled with said spring member, said terminal member being provided with a concave end for receiving an end of said plug member in cooperative electrical contact therewith, said plug member having a set of opposite edges for engaging the individual coils of said spring member, said plug member further having a width approximately equal to the major axis of said elliptical cross section to cause torsional displacement of spaced coils relative to one another upon insertion of said plug member into said spring member, whereby contact pressure between said edges and said coils after insertion of said plug member into said spring member is afforded by said torsional displacement of said spring member.

9. An electrical connector comprising a helically wound metal spring member having an elliptical cross section when viewed axially thereof, said spring member comprising a plurality of springs having their individual coils disposed in interlaced relationship with one another, and at least one elongate metal plug member adapted for insertion into said spring member, one of said members being axially twisted, said plug member having a set of opposite edges for engaging the individual coils of said spring member, said plug member further having a width approximately equal to the major axis of said elliptical cross section to cause torsional displacement of spaced coils relative to one another upon insertion of said plug member into said spring member, whereby contact pressure between said edges and said coils after insertion of said plug member into said spring member is afforded by said torsional displacement of said spring member.
